MATERIAL HANDLING SCOOP

David F. McLeod, Worthington, Minn.

Application May 16, 1949, Serial No. 93,574

1 Claim. (Cl. 294—55)

1

This invention relates to improvements in utility devices designed for moving such materials as snow, leaves or the like and is directed particularly to a device of such character which can be easily operated by hand.

A principal object of the present invention is to provide a material moving device of the character stated which is in the form of a large scoop having a handle connected therewith and constructed in such manner that it may be easily and quickly moved in the nature of a toboggan over the surface of the ground or over a snow or ice covered area, for the purpose of picking up snow, grass, leaves or other material of a like nature so that the same may be easily transported to a disposal point.

Another object of the invention is to provide a device of the character stated which is light but strong and durable and which is constructed in the novel manner whereby it may be collapsed and folded for easy transportation or storage.

Still another object of the invention is to provide a hand operated device of the character stated having a solid metal bottom and fabric side and back walls, with novel means for maintaining the side and back walls in set up condition for use, provision being made for the operation of the device by means of a rearwardly extending handle which is connected to the frame portion of the device which maintains the fabric walls in position.

Still another object of the invention is to provide a device of the character stated wherein the solid bottom or floor portion is constructed with a rear upwardly curved part which may be employed as a toboggan runner, after the device is filled with the material to be moved, by tipping the filled device back so that it rests entirely upon the curved rear end portion whereby it may be easily moved around on such portion.

Still another object of the invention is to provide a device of the character stated having a readily attachable rake element designed to be mounted across the forward edge of the bottom thereof to facilitate picking up leaves, twigs, cut grass, or other particles of a like character.

The invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

2

In the drawing:

Figure 1 is a view in perspective of a scoop constructed in accordance with one embodiment of the present invention.

Figure 2 is a sectional view taken in a vertical plane longitudinally of the device illustrated in Figure 1 and on an enlarged scale.

Figure 3 is a fragmentary detail showing the connection between one side of the wall supporting frame and the bottom of the device.

Figure 4 is a view in perspective of another embodiment of the invention wherein the side and back walls are of rigid material.

Figure 5 is a fragmentary detail showing in top plan detachable connections between certain of the parts.

Figure 6 is a detail view illustrating one manner of connecting the brace arms to the handle.

Figure 7 is a fragmentary detail of the connection between the brace and handle of the embodiment shown in Figure 4.

Figure 8 is a view in perspective of still another embodiment of the invention showing the use of a fabric wall structure.

Figure 9 is a sectional view taken on the line 9—9 of Figure 8.

Figure 10 is a view in perspective of the embodiment shown in Figure 8 but showing the use of rigid walls.

Figure 11 is a detail view of a rake element designed for use in connection with the embodiments illustrated in Figures 8 and 10.

Referring now more particularly to the drawings, Figures 1 to 3 inclusive show an embodiment of the present invention wherein the side and back walls may be constructed of a suitable heavy fabric to thereby produce a structure of minimum weight.

In this first embodiment of the invention there is provided a bottom wall or bottom plate which is generally designated 10 and which has the straight front edge 11, the upturned side edge flanges 12 and an upturned rear edge portion 13 which is turned on a relatively wide curve whereby to provide a transverse back runner or toboggan sole on which the filled receptacle may be slid.

The numerals 15 and 16 designate respectively side and back walls. These latter walls are constructed of a suitable heavy fabric such as canvas or the like and the top edges of the walls are defined by the guide sleeves 17. The lower edge portions of the side and back walls are secured to the parts 12 and 13 of the bottom in any suit-

able manner as by the use of rivets 18 or the like.

Bordering the top edges of the side and back walls is a frame formed of steel or other suitable material and comprising the side rails 19 and back rail 20.

At the free end of each side member 19 of the frame there is formed an eye 21 and in this eye is connected a corresponding eye 22 of a front leg 23 for the frame which extends downwardly to the adjacent corner of the bottom 11.

Upon the bottom 11 at each side and adjacent to the forward edge there is secured by welding or in any other suitable manner, a hinge sleeve 24 and into this sleeve is inserted the right angularly extended lower end portion 25 of the adjacent leg 23. This angular extension 25 forms a hinge pin which is inserted into the sleeve 24.

Upon the top of each sleeve 24 is secured an ear 26 to which is pivotally attached by a bolt 27 or in any other suitable manner, an end of a supporting brace arm 28. This arm extends upwardly and is inclined slightly rearwardly as shown in Figure 1 and is provided with a suitable notch in its rear edge as indicated at 29, for engagement with a pin 30 carried by the adjacent side rail 19 of the frame.

Secured to the back or cross rail or bar 20 of the frame, midway between the ends thereof, is the upwardly and rearwardly extending handle 31, across the upper or outer end of which is the transverse hand bar 32. The sleeve 17 of the material of the back wall 16 is, of course, provided with a suitable opening so that the handle 31 may extend through and also extending through such opening and rigidly secured to the lower end of the handle 31 or the rail 17, is a forwardly extending eye or clevis 33.

Secured to the clevis 33 by bolt or pin 34 is the eye 35 which is formed at the upper end of a brace rod 36. This brace rod extends downwardly across the inner or forward face of the back wall 16 and is turned at its lower end to provide a hook 37 similar to the hooked end 25 of a leg 23. This hook 37 at the lower end of the brace rod 36 is engaged through an eye 38 which is fixed to the bottom plate of the device upon the upwardly curving rear part 14 thereof as shown in Figure 2. Thus, by means of the brace rod 36, the collapse of the wall structure is prevented when downward pressure or force is applied to the handle 31 for the purpose of sliding the unit forwardly to scoop up snow or other material.

In order to further stabilize the structure, there is secured at the opposite corners of the wall bracing frame, the inwardly converging brace rods 39 which are brought into overlapping relation and receive, in suitable apertures, a bolt 40 which is carried by the handle and upon which is threaded the nut 41 to maintain the brace arms 39 firmly in position.

In the embodiment of the invention illustrated in Figure 4 the side and back walls of suitable rigid material are employed. In this embodiment the bottom plate is designated 42 and the opposite side edges are turned up slightly as indicated as 43.

The side and back walls 44 and 45 are attached by hinges 46 and 47, respectively, to the bottom plate 42, with the side walls at the inner sides of the upturned portions 43. The hinges 46 and 47 are so positioned that the walls may be folded inwardly one over the other. When the back wall is folded in first the side walls may then be folded down one on top of the other and both

upon the back wall so as to collapse the structure into a substantially flat body.

When the side walls and back walls are set up for use the same may be secured together by means of a latch 48, here shown as being carried by a side wall, and a keeper 49 shown as being carried by the back wall. However, the invention is not limited to this specific connection but it is obvious that any suitable connecting means may be employed.

The numeral 50 designates the handle which at its lower end lies against the inner face of the back wall 45 and the lower end of this handle is connected with a substantially U-shaped frame 51 consisting of the transverse back portion 52 and the forwardly and downwardly curving side portions 53.

At the free lower ends of the side portions 53 of the frame are formed the eyes 54 each of which has extended therethrough a pivot pin or bolt 55 which passes through and is maintained in position by two spaced apertured ears 56 which are secured to the bottom plate 42 adjacent to a front corner as shown in Figure 5.

Passing through the lower end of the handle 50 and also through the back wall 45, is an eye bolt 57, the eye portion 58 of which lies upon the forward side of the handle. A nut 59 threaded upon the rear end of the bolt bears against the rear side of the back wall 45 and draws the handle and wall tightly together.

The numeral 60 designates a brace rod corresponding to the brace rod 36. The upper end of this brace rod is provided with one or a pair of eyes 61 which are positioned in side by side relation with the eye 58 of the eye bolt 57 to receive a connecting bolt or pin 62. The brace rod 60 extends downwardly and is secured at its lower end in a suitable manner to the plate 42, in a manner similar to that in which the brace rod 36 is secured to the bottom plate 10, or in any other suitable manner.

As shown in Figure 5 the spaced eyes 56, which form bearings for the pins 55, are spaced apart a distance materially greater than the thickness of the eye 54 which is positioned therebetween. This arrangement provides for the attachment across the front edge of the bottom plate 42 of the scoop, of a fork or rake unit which is generally designated 63. Such unit may be of any suitable character but is here shown as consisting of a transverse back bar 64 to which are attained a number of forwardly extending fingers or tines 65. At each end of the bar 64 is secured a hinge ear 66 which is suitably apertured and extends rearwardly to be positioned between a pair of ears 56 and to have extended through it the adjacent pivot or coupling pin 55 in the manner shown in Figure 5. The tines 66 are suitably formed upon their under sides to provide curved riding surfaces which will facilitate their movement over the surface of the ground without allowing the points of the tines to dig into the ground. Of course, when the scoop device is used for removing snow or similar material his rake unit 63 will be removed.

In the use of the present invention in either of its forms the device is shoved over the surface of the ground flat upon the bottom plate 10 or 42 to pick up snow or other material which is to be moved. After the scoop has received a suitable load the operator bears down upon the rear end of the handle so as to tilt the scoop onto the curved back portion 14 or on the back corner 75 of the bottom plate 42 and then uses this curved

back portion of the bottom plate as a toboggan to slide the scoop over the surface of the ground to the disposal point.

When the desired use has been made of the scoop the same may be readily folded and stored away. In the case of the embodiment illustrated in Figures 1 and 2 the brace or latching arm 28 is disengaged from the pin 30 adjacent thereto and the brace rod 36 is disengaged from the back portion of the bottom plate whereupon the canvas walled sides can be folded in onto the bottom.

With regard to the form shown in Figure 4 the U-frame is removed by disconnecting the forward ends 54 from the bottom plate and by removing the eye bolt 57 and disconnecting the brace arms 67 from the handle, such arms being attached to the handle in the manner illustrated in Figure 6. The back may then be folded down and the side walls folded in and the parts readily stored away.

Figures 8 to 11 illustrate a further embodiment of the invention wherein the handle structure is attached to the forward portion of the bottom of the device and is braced against the said bottom of the device at the rear of the latter so that a firm rigid construction is obtained and at the same time the device can be easily and quickly folded or collapsed.

This additional embodiment of the invention also provides for the use of either rigid wall portions or walls of flexible material such as canvas or the like.

In this latter embodiment the bottom is generally designated 75 and comprises a suitably large rectangular plate 76 having the upstanding side and back walls designated respectively 77 and 78.

The handle is generally designated 79 and is of substantially U-shape, comprising the spaced parallel side arms 80 and the transverse connecting portion 81 which provides the handle bar or hand grip for the device.

The handle unit 79 is positioned with the free end portions against the inner sides of the walls 77 at the forward ends of the latter and passing through the side portions 80 are the pivot bolts 82, each of which is connected to the adjacent side wall. By this means the handle unit 79 as a whole can be swung downwardly toward the back wall 78 when desired.

Each of the handle portions 80 at its free end has the flat obtusely angled foot 83 which extends forwardly beyond the forward edge 76' of the plate 76 and is substantially horizontal when the handle unit 79 is set up for use.

Each foot portion 83 is suitably apertured to have a bolt 84 pass therethrough. The foot portions 83 are provided for the detachable support, forwardly of the edge 76' of the bottom plate 76, of a scrapping blade 85 such as that illustrated or a toothed rake blade 86. These blades are provided with suitable openings for the extension of the bolts 84 therethrough whereby the blades are supported forwardly of the edge of the bottom plate 76.

It will be readily seen that when the handle unit 79 is swung downwardly on the pivot bolts 82 the blade 85 or the rake blade 86 will be swung upwardly away from the supporting surface.

Extending transversely between the side members 80 of the handle unit is a second handle bar which is designated 87 and which parallels the bar 81. This second bar 87 facilitates the maintenance of the device in backwardly tilted position

when it is desired to elevate the forward edge or it may also be used when dumping the scoop.

In addition to functioning as an extra handle bar, the bar 87 also provides means for the pivotal connection to the handle unit 79, of a brace unit which is generally designated 88 and which is in the form of an upright U-shaped frame having the bottom horizontal bar 89 and the upstanding side arms 90. The side arms 90 are provided at their free ends with the hinge eyes 91 through which the bar 87 passes. Thus the brace unit 88 is swingingly supported on the bar 87 and the overall width of this brace unit is such that it conveniently fits between the side walls 77 of the bottom portion of the scoop so that the bar 89 will rest in the angle between the bottom plate 76 and the back wall 78.

To facilitate the maintenance of the brace unit 88 in bracing or propping position for the handle unit 79, the back wall is provided with one or more suitable spring clips 92, which are secured by screws, bolts or the like as indicated at 93 to the back wall 78. The bar 89 slips under the clips 92 and is firmly held in propping position as shown.

The embodiment of the invention shown in Figures 8 to 11 is designed to have fabric back and side walls which form continuations of the rigid walls 77 and 78.

As illustrated in Figure 8 a flexible fabric wall is shown and generally designated 94. This flexible fabric wall is preferably formed in one piece but is shaped to provide the side wall portions 95 and the back wall portion 96.

The bottom edges of the side and back wall portions 95 and 96 are suitably secured by rivets or the like to the adjacent walls 77 and 78 respectively of the bottom of the structure as illustrated and the top edge of each side wall portion 95 is shaped to provide a sleeve 97 which encloses the adjacent side member 80 of the handle unit. The top edge of the back wall portion 96 is likewise formed to provide a sleeve or hem 98 through which the bar 87 passes.

If it be preferred that the fabric wall be discarded for rigid side wall and back wall extensions the side and back walls 77 and 78 of the bottom portion are provided with suitable slots 99 for the connection of rigid side and back wall extensions 100 and 101 respectively. These extensions are in the form of plates of metal of suitable height and length and each is provided at its bottom edge with a flat hook tongue 102 which is adapted to engage in a slot 99.

At the two ends of the back wall extension 101 a right angled flange 103 is formed, against the inner side of which the adjacent wall 100 positions and above this flange the back wall portion 101 has the outwardly extending tongue 104 which is designed to be received in the slot or notch 105 formed in the longitudinal edge of a long flat hook member 106, at one end of the latter. The other end of the hook member is pivotally attached as at 107 to the adjacent wall extension 100. With this arrangement it will be readily seen that the low walls or flanges 77 and 78 of the bottom portion are extended by the wall extensions 100, 101 whereby there is provided a scoop structure which may be used for heavier work and which has rigid walls for that purpose.

In order to facilitate the tipping and dumping of the scoop the back part of the back flange 78 is provided with a hand grasp or handle 108, as shown.

I claim:

In a material handling scoop, a metal body having a flat rectangular bottom, interconnected flanges upturned from the side and back edges of the bottom, an inverted U-shaped handle having the lower ends of its leg portions disposed at the inner sides of the forward ends of the said side flanges, pivots connecting said leg portions to the side flanges, a transversely disposed bar connecting said leg portions intermediate their ends, a brace member of substantially U-form having the free ends of its leg portions hingedly connecting said bar adjacent the ends thereof and its medial transverse portion adapted to bear against the lower portion of the said back flange when the handle is swung into an upwardly and rearwardly inclined position, spring clips spacedly mounted on the inner side of the said back flange to engage over the said medial portion of the brace member to maintain the handle in said inclined position, foot portions out-turned from the free

5
10

ends of the first leg portions, a blade extending between and secured to the lower sides of the foot portions, other flanges up-turned from the opposite ends of the blade and adapted to move into overlapping relation with respect to the outer sides of the adjacent ends of the said side flanges when the handle is swung rearward and downward to swing the blade into position to close the forward end of the body, and side and back walls of a flexible material connecting the top edges of said side and back flanges with said bar and the first leg portions between the bar and the pivots.

DAVID F. McLEOD.
